UNITED STATES PATENT OFFICE.

ALBERT BAUMGARTEN, OF FREEPORT, ILLINOIS.

BOTTLE-HOLDER.

No. 853,151.

Specification of Letters Patent.

Patented May 7, 1907.

Original application filed June 15, 1903, Serial No. 161,426. Divided and this application filed August 19, 1905. Serial No. 274,956.

To all whom it may concern:

Be it known that I, ALBERT BAUMGARTEN, a resident of Freeport, in the county of Stephenson and State of Illinois, have invented 5 certain new and useful Improvements in Bottle-Holders, of which the following is a full, clear, and exact description.

The invention relates to devices for holding bottles, jars and the like.

10 This application is a division of an application filed by me June 15, 1903, serial number 161,426.

15 The invention designs to provide an improved construction of bottle holders for cork-pullers, corking-machines and the like, which are simple in construction and which can be produced at a low cost.

20 The invention consists in the several novel features hereinafter set forth and more particularly defined by claim at the conclusion hereof.

25 In the drawings: Figure 1 is a front elevation of a bottle-holder embodying the invention, the same being shown in use on a cork-puller. Fig. 2 is a view in horizontal section, taken on line 2—2 of Fig. 1. Fig. 3 is a detail view of one of the holder-jaws of the bottle-holder. Fig. 4 is a detail of the front guide for the holder. Fig. 5 is a detail of the 30 frame-pivots for the holder-jaws.

35 A denotes a suitable supporting frame such *e. g.* as a cork-puller frame, which is usually made of sections and provided with a clamp whereby the device can be secured to a table or counter.

40 The improved bottle-holder comprises a pair of jaws H and H', each of which is provided with a handle h, at its free end, and an open seat h' formed between lugs h², h³ integrally formed with the jaws. The frame is formed with integral depending pivot-studs A⁴, connected by an integral cross-bar A⁵. Seats h' are adapted respectively to fit 45 around studs A⁴ and thereby the jaws are pivotally sustained. Lugs h² are adapted to fit snugly between cross-bar A⁵ and the lower portion of frame A and thus the jaws are confined against vertical play. A spring J seated in a pocket h⁴ in each of the jaws, 50 tends to hold the jaws in open position and holds the seats against the pivot-studs. Thus the jaws are removably and pivotally sustained. The free ends of the jaws are guided and held in a depending loop A⁷ integrally

formed with one of the frame-sections. Re- 55 sultant advantages of this construction are, the jaws can be detached from the frame by forcing the pivoted-ends toward each other sufficiently to free the seats from the studs, when it is desired to employ the puller without a holding-device, *e. g.* when a bottle or jaw with an unusually large neck is to be placed beneath the puller, and for convenience in packing for shipment, and furthermore the use of separate pivot-bolts or 60 screws is avoided.

65 The invention is not to be understood as restricted to the precise form shown and described, but may be modified within the scope of the claims without departing from 70 the spirit and scope of the invention.

Having thus described the invention, what I claim as new and desire to secure by Letters Patent, is:

1. In a bottle-holder the combination of a 75 support, a pair of jaws each having a separable pivotal connection with the support, each connection comprising a pivot, and an open seat, and means for retaining the pivots and seats in connected relation. 80

2. In a bottle-holder the combination of a support, a pair of jaws each having a separable pivotal connection with the support, each connection comprising a pivot and an open seat, and means for yieldingly retaining 85 the pivots and seats in connected relation.

3. In a bottle-holder the combination of a supporting frame, a pair of jaws having open seats formed therein, pivot-studs fixedly secured to the frame, and means removably holding said jaws in position to be retained by said pivots. 90

4. In a bottle-holder the combination of a supporting frame, a pair of jaws having open seats formed therein, pivot-studs fixedly secured to the frame, and a spring pressing 95 said jaws into position to be retained by said pivots.

5. In a bottle-holder the combination of a supporting frame, a pair of jaws having open 100 seats formed therein, pivot-studs integrally formed with the supporting-frame, and a spring between the jaws and holding the jaws seated about said pivots.

ALBERT BAUMGARTEN.
